UNITED STATES PATENT OFFICE.

GEORGE W. VAN SICKLE, OF BURLINGTON, IOWA, ASSIGNOR TO J. H. BRAMHALL AND NOTT S. HAMMACK, OF SAME PLACE.

TONGUELESS CULTIVATOR.

SPECIFICATION forming part of Letters Patent No. 271,164, dated January 23, 1883.

Application filed July 3, 1882. (No model.)

To all whom it may concern:

Be it known that I, GEO. W. VAN SICKLE, of Burlington, of the county of Des Moines, in the State of Iowa, have invented a new and useful Improvement in Double Arched Tongueless Cultivators, which improvement is fully set forth in the following specification, reference being had to the accompanying drawing.

My invention relates to improvements in double arched tongueless cultivators with metal frame-work, in which a metallic spring is attached at one end to the upright of the axle frame-work and at the other end to the under prong of the plow-beam. I attain these objects by the mechanism illustrated in the accompanying drawing, in which the figure is a side view of the cultivator as it appears with the wheel removed on the one side and the plows on the other side.

Similar letters refer to similar parts. My improvement consists in an attachment to a double arched tongueless cultivator, in which the cross-bar A is a flat bar of metal firmly attached to axle B in a horizontal position and at right angles with the same. The outer edge of the bar A is turned up and provided with two braces, c and c', one on each side of the axle, having perforations d and d', through which the arches e and e' pass.

Bar A is further provided on each side of

axle B with the sockets f and f', to act as receptacles for the corresponding ends of the arches e and e', so as to enable the arches to turn in these sockets.

To cross-bar A there is further attached, by bolt or otherwise, an upright, X, to the top of which spring R, of suitable material and of convenient shape and size, is attached, which passes to the front over arch e', then turns around downward, passes under arch e', and on further also under arch e, (or it may pass over e,) turns again downward and under axle B, and is fastened to the lower prong, K, of plow-beam S.

What I claim as my invention is—

1. In a double arched tongueless cultivator, the cross-bar A, provided with braces c and c', and the arches e and e', in combination with the upright X and spring R, substantially as and for the purpose described.

2. In a double arched tongueless cultivator, the cross-bar A, provided with braces c and c', the arches e and e', the upright X, and spring R, in combination with the axle B, substantially as and for the purpose described.

GEO. W. VAN SICKLE.
